UNITED STATES PATENT OFFICE.

CLARENCE C. ROGERS, OF WHEELING, WEST VIRGINIA.

EXPLOSIVE-ENGINE.

1,091,766.

Specification of Letters Patent. Patented Mar. 31, 1914.

Application filed July 16, 1913. Serial No. 779,366.

To all whom it may concern:

Be it known that I, CLARENCE C. ROGERS, a citizen of the United States, residing at Wheeling, in the county of Ohio and State 5 of West Virginia, have invented a new and useful Explosive-Engine, of which the following is a specification.

The present invention relates to improvements in explosive engines, one object of the 10 invention, being the provision of a structure by means of which the explosive charge and the compression chamber of the engine will be proportionately reduced or increased, to in a single engine produce a structure capable 15 or varying horse power, thus providing means whereby the fuel consumption will be regulated entirely by the horse power and so that a great economy in the use of fuel will result.

20 A further object of the present invention, is the provision of a mechanism for simultaneously operating a compression chamber regulating means and the throw of the intake valve so that a proportionate amount 25 of charge is admitted according to the limited or increased volume of the cylinder.

With the foregoing and other objects in view which will appear as the description proceeds, the invention resides in the combination 30 and arrangement of parts and in the details of construction hereinafter described and claimed, it being understood that changes in the precise embodiment of the invention herein disclosed can be made 35 within the scope of what is claimed without departing from the spirit of the invention.

In the drawings—Figure 1 is a side elevation of a single cylinder engine with the intake and exhaust valve portion thereof in 40 section. Fig. 2 is a section taken on line 2—2 of Fig. 1. Fig. 3 is a top plan view. Fig. 4 is a detail view of the valve stem and the co-operative means carried thereby and in the path thereof for limiting the movement 45 of the same and its valve.

Referring to the drawings, the numeral 1 designates the base of the engine which has mounted therein a crank shaft 2, to which is connected the piston rod 3. Carried by the 50 piston rod 3 is the usual power piston 4 mounted for reciprocation within the cylinder 5, the cylinder being divided by the dotted line into the compression chamber 7 and the piston displacement 6.

55 In order to control the admission of the explosive charge to the cylinder of the en-

gine, an intake valve 8, which is indicative of any form of valve, is provided, and in the present instance it is provided with the valve stem 9, the spring 10 of which normally holds the valve seated. This stem is 60 operated through any mechanism from the crank shaft 2 to be mechanically opened to admit of the charge of carbureted air at the proper time within the cylinder of the engine. In the lower end of the stem 9 or in 65 any convenient part thereof is provided the tapered slot 11 into which is adapted to fit the sliding wedge 12, said wedge 12 being disposed for sliding movement in the 70 brackets 13, the operation of said wedge being such as to, through the slot 11, regulate the movement of the stem 9 and consequently the relative movement of the valve 8 from its seat.

75 A member 14, constructed in the nature of a piston with packing rings 15 upon the smooth portion of its periphery and with the upper portion of the periphery provided with threads 16, is disposed in the upper end of the cylinder, the threads 16 engaging the threads 17 formed in the adjacent wall of the cylinder, so that when the member 14 is rotated, the coaction of such threads will cause the member 14 to be 80 moved to and from the center of the cylinder so as to increase or decrease the compression chamber 7.

85 The operating stem 18 of the member 14 is mounted for sliding and rotary movement in the stuffing box 19 disposed concentrically of the head of the cylinder 5 and upon the upper end of the stem 18 is keyed a pinion 20, which as shown is in mesh at 90 all times with the teeth of the horizontally disposed rack 22. This rack 22 is mounted for reciprocation within the supports 21 mounted upon the exterior of the head of the engine and carrying the looped portion 23 which is connected to the operating and 95 controlling lever 24. This lever has its lower end pivoted in the lug 25 carried exterior of the base of the engine and carries the adjustable bolt held device or connection 26, which is pivotally connected at one end 100 to the wedge 12 and through the lever 24 as illustrated in Fig. 2. By this means the wedge may be adjusted at will. By this means, it will be seen that when the lever 24 is operated that both the rack 22 and 110 the wedge 12 will be operated simultaneously and that such action will increase or decrease

the compression area 7 of the engine and at the same time permit of the increase or decrease in the relative movement of the valve 8. These elements are so constructed, 5 that the proper proportion of carbureted air is admitted into the cylinder of the engine relatively to the compression chamber or space 7, so that with this structure an engine may be economically run at an exceedingly 10 low or a comparatively high horse power.

What is claimed is:

An explosive engine, having a cylinder, an intake valve, a slidable and rotatable compression chamber regulating member 15 mounted in the head of the cylinder, a stem disposed concentrically of and through the cylinder head and carrying the member, a pinion carried by the stem, a toothed rack

mounted exteriorly of the cylinder and engaging the pinion to rotate the member, the 20 stem of the intake valve being provided with a wedge shaped slot, a sliding wedge mounted upon the cylinder and disposed to coact with the slot of the stem to regulate the throw of the valve, and a lever connected to the wedge and rack, whereby the compression chamber regulating member and wedge are operated simultaneously.

In testimony that I claim the foregoing as my own, I have hereto affixed my signature 25 in the presence of two witnesses.

CLARENCE C. ROGERS.
